UNITED STATES PATENT OFFICE.

WILLIAM MCNAUGHT, OF ROCHDALE, ENGLAND.

WOOL-WASHING MACHINE.

SPECIFICATION forming part of Letters Patent No. 650,727, dated May 29, 1900.

Application filed August 9, 1897. Serial No. 647,577. (No model.)

To all whom it may concern:

Be it known that I, WILLIAM MCNAUGHT, residing at Rochdale, in the county of Lancaster, England, have invented certain new and useful Improvements in Machines for Scouring and Washing Wool and other Fibrous Materials, (for which Letters Patent have been obtained in England, dated April 10, 1894, No. 7,133;) and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has relation to machines for scouring and washing wool and other fibrous materials, and has for its object certain improvements in the construction of the washing-trough and in the mechanism for actuating the propelling and immersing rake, as will be described hereinafter and as shown in the accompanying drawings, in which—

Figure 1 is a side elevation of a fiber scouring or washing machine constructed in accordance with my invention and provided with an immersing or propelling rake of well-known construction, a portion of the side walls of the tank being broken away. Fig. 2 is a top plan view of Fig. 1, the mechanism for propelling the rake and the supporting-standards for said mechanism being removed. Fig. 3 is a side elevation of the machine with the improved form of immersing and propelling rake, a portion of the side walls of the tank being broken away, as well as the feed and delivery aprons. Fig. 4 is a top plan view of Fig. 3, the rake, its propelling mechanism, and the supporting-standards for the latter being removed. Fig. 5 is a vertical transverse section of the tank shown in Figs. 1 to 4, the rake and part of its propelling mechanism being removed. Figs. 6, 7, and 8 are detail side, end, and top plan views, respectively, of a portion of the improved immersing and propelling rake. Fig. 9 is a longitudinal vertical section of the feed-end portion of the machine drawn to an enlarged scale and showing the rake-operating mechanism. Fig. 10 is a like transverse section looking toward said feed end of the ma-

chine. Fig. 11 is a detail sectional view of the tank looking toward the feed end and showing the perforated distributing-plate 55 through which the scouring or washing liquid is fed to said tank; and Figs. 12 to 20 are cross-sectional views of variously-modified scouring or washing tanks, the settling-chamber being omitted from each of them. 60

One of the objects of this invention is to obviate the removal of the false bottom and yet afford proper means whereby the trough or tank can be thoroughly or effectually cleansed. This I accomplish by so constructing the tank-bottom that the sedimentary matter will be directed to a line or lines of lowest level extending the full length of the tank, from which the sedimentary matter can be readily removed, and by so constricting 65 the tank or trough that free access may be had to such line or lines of lowest level, means being also provided for washing or flushing the sediment from the tank-bottom. 70

In Fig. 5 I have shown a tank *a*, having its bottom *a'* inclined from one side to the other to form a collecting gutter or channel *a*² along the right side of said tank at the lowest point thereof, while the washing-trough proper, *b*, is narrower than the said tank, so as to leave 80 a space *b*¹¹ between the inner vertical wall *b*⁴ of said trough and the right-hand outer wall of the tank *a*, whereby ready access is had to the collecting gutter or channel *a*² for the purpose of removing the sedimentary matter, a 85 normally-closed discharge-opening *a*²¹ being provided in said gutter about midway of its length. The inner wall *b*⁴ of the washing-trough *b* is or may be perforated. Of course the space *b*¹¹ may be on the left side of the 90 tank, Fig. 16, or there may be such a space *b*¹¹ and *b*¹² on each side of said tank, Fig. 14, according as a wide or narrow tank is used, or said space or spaces may be omitted altogether, as shown in Figs. 15, 17, and 20. 95

For the purpose of washing or flushing off the sedimentary matter that may collect on the inclined bottom *a'* of the tank I arrange a perforated pipe *i*, extending along the highest point of said bottom, through which water is forced for the purposes stated. 100

The object referred to may be attained in many different ways. For instance, as shown in Fig. 12, the bottom *a*¹¹ may be constructed

to converge from opposite sides of the tank to the center, with the space b^{11} on the left side, or the trough b may be so arranged as to form such a space on opposite sides thereof, as shown in Fig. 13 at b^{11} and b^{12} , or said space or spaces b^{11} and b^{12} may be omitted, Fig. 15. The tank-bottom may also be made to diverge from a higher central point to a lower point on opposite sides, as shown at a^{12} , Fig. 18, or said bottom may be made concave, as shown at a^{13} , Figs. 19 and 20, and the tank provided with an open space on one or both sides of the washing-trough proper, b , or said space or spaces may be omitted. In all of these constructions there is a flushing-pipe i at the highest point or points of the tank-bottom for the purposes above set forth.

I am of course aware that it is not broadly new to provide a vessel or tank with a bottom constructed as described; but I believe I am the first to apply this construction to a machine for scouring and washing fibrous materials and provide suitable means for flushing the bottom, together with means for gaining access thereto, without removing the false bottom usually provided.

The machine is provided, as usual, with an endless feed lattice or apron d at one end and a like delivery lattice or apron d' at the opposite end, in rear of the usual squeeze-rolls e and e' , and the tank a with the usual delivery incline or chute b^2 .

It has before my invention been the general practice in scouring and washing fibrous materials to pump, lift, or otherwise transfer the liquid squeezed out of the fibrous material at the delivery end of the trough immediately back thereto. As is well known, this liquid holds considerable quantities of impurities in suspension, which are thus returned to the washing-trough, so that the liquid therein becomes too foul for use in a comparatively-short time. A further object of my invention is to avoid this disadvantage by providing a settling tank or chamber wherein this liquid is allowed to stand and settle before it is returned to the trough. To this end there is an open settling tank or chamber c , arranged along one side of the tank a , Figs. 2, 4, and 5, the bottom c' of which tank or chamber is also inclined from the side wall of the tank a or inner wall of the settling-chamber to the outer wall thereof to form along the latter wall a collecting gutter or channel c^2 for the collection of sedimentary matter, which can be removed through a normally-closed purging-opening c^{21} about midway of the length of said gutter or channel c' , Figs. 2, 4, and 5. From the settling-chamber leads a conduit e^3 , that is connected with a collecting-trough e^2 beneath the squeeze-rolls e e' , Figs. 1, 3, and 4. At the opposite end the settling-chamber c is connected with a centrifugal pump j , that forces the liquid back to the washing-trough b above its perforated bottom b' . In order that this returned liquid may be uniformly distributed over the width

of said washing-trough, I provide the washing-tank a at its feed end with a receiving-chamber j^6 , to which the centrifugal pump j is connected through a pipe j^4 , that has a suitable stop-cock j^5 for regulating the quantity of liquid passing through said pipe, or the said delivery-pipe j^4 of the pump j may be connected with a vessel f , into which steam is blown through pipe f' for the purpose of heating the liquid before it reaches the chamber j^6 , as shown in Fig. 3. This chamber has its front wall j^7 partly inclined upwardly and rearwardly and partly vertical, the upper vertical portion j^{16} being provided with a line of perforations or openings j^7 , Figs. 9 and 11, on a line with the normal level of liquid in the trough, or substantially so.

In Fig. 1 I have shown a propelling-rake the general construction of which, except the immerser portion, is well known, said immersing portion being preferably constructed as hereinafter described.

In Figs. 3, 6, 7, and 8 I have shown a propelling and immersing rake II, which is composed of two longitudinal tubular girders h h , to which is secured a box-like framing h^b , the bottom h^{18} of which is of zigzag form in longitudinal section and provided at the points where the sides of the angles join each other and the sides of the framing with prongs or teeth h^8 , the bottom h^{18} being perforated to admit of the free passage of liquid therethrough, as shown in Fig. 8 on the left-hand side, in which a portion only of the bottom is shown as perforated.

The entire rake may be constructed as described or the box-like framing may be arranged in sections, as shown on the right-hand end of Fig. 3, and it is obvious that as the rake moves through the trough b toward the delivery end the fibrous material will be moved in the same direction below the surface of the liquid, as the boxes prevent it from rising and floating, a portion of such material being swept over the delivery end b^2 by the teeth at the forward end of the rake, which is devoid of the box-like framing at its said delivery end, as shown in Fig. 3. As usual, the rake after completing its forward movement rises sufficiently to bring its teeth clear of the level of the liquid in the trough b , then moves backward, and finally downward into the liquid of the trough, whereby substantially the whole of the material therein, as well as the material fed thereto, is at once immersed to be dragged a step forward, proportionate to the sweep of the rake, and so on.

It is obvious that with a rake constructed as described the scouring or washing of the fibrous material is not only expedited, but is more uniform and more thorough than would be the case with a rake of usual construction.

On one of the side walls of the tank a and on the inner wall b^4 of the washing-trough b are secured standards S S and S' S' , provided at their upper ends with bearings for cross-

shafts s and s' , respectively. To each of said cross-shafts are secured two levers L M and L' M' , respectively, the levers L and L' being three-armed levers and the levers M and M' two-armed levers, Figs. 5, 9, and 10. The arms l and m of the said levers carry each a weight h^x , said weights counterbalancing the weight of the rake H , or substantially so, as usual, and the arms l' and m' are connected by rods h^2 with cross-bars h^9 below the tubular girths h of said rake H , Fig. 10, while the arms l' of the three-armed levers L L' are connected together by a rod h^6 . The upper end of the suspension-rods h^2 are screw-threaded and screw into a forked coupling h^5 , Fig. 10, so that the amplitude of the rising-and-falling movements of the rake H can be regulated within certain limits by lengthening or shortening the connection between the said 20 rake and the lever-arms.

It is obvious that when one of the shafts s or s' is rocked or oscillated the other will likewise be rocked or oscillated, through the connecting-rod h^6 , to impart to the rake H the required rising-and-falling motion. This movement of the rake and the required to-and-fro motion or sweep is imparted to said rake through the following mechanism, supported from the standards S S at the feed end of the 25 machine: There is a rod h^8 , one end of which is pivoted to the arm l' of lever L , the other end of said rod h^8 being pivoted to a lever k' , that is fulcrumed at k^2 to an arm projecting rearwardly from one of the standards S . The 30 lever k' carries near its left end a roller k^9 , that rides on a cam k^4 , secured to a short shaft k , Fig. 10. On the inner end of shaft k is a crank k^5 , whose crank-pin carries a roller that works in the longitudinal slot of a lever 35 l^3 , fulcrumed at l^4 , and to the lower end of said lever l^3 is pivoted one end of a connecting-rod l^6 , whose opposite end is pivoted to a cross-bar h^a , secured to the longitudinal girths h of the rake H , Figs. 9 and 10. The short 40 shaft k carries at its outer end a toothed wheel k^a , in gear with a pinion k^6 on the driving-shaft h^{10} , that carries, as usual, a fast and a loose belt-pulley k^7 and k^{17} . The arrangement of the described mechanism is such that 45 the crank-pin on crank k^5 of shaft k is moving through the lower half of its circle during the movement of the rake through and toward the delivery end of the washing-trough b —that is to say, when the rake is in 50 its lowermost position and said crank-pin moves through the upper half of its circle during the backward movement of the rake or when the rake is lifted with its teeth clear 55 of the liquid in said trough.

50 In the position of the rake-operating mechanism, Fig. 9, the lever l^3 , under the action of the crank k^5 , is slowly moving the rake H toward the delivery end until said crank is about to travel from its lower to its upper 55 half-circle, at which time the cam k^4 , acting on rod h^3 , moves the arm of lever L upward, thereby revolving shaft S toward the right,

which movement is communicated to lever M on said shaft, and through connecting-rod h^6 to lever L' , shaft S' , and lever M' thereon, 70 whereby the rake H is lifted out of the liquid in trough b . As said crank revolves through the upper half of its circle and in the upper portion of the slot in lever l^3 the rake will be moved backward at an increased speed and 75 then downward back into the liquid in the trough b , as will be readily understood. The path described by the rake-teeth points is shown at x , Fig. 9.

The rods h^6 , h^3 , and l^6 are, like the suspension-rods h^2 , screw-threaded at one end and screw into forked couplings for purposes of adjustment.

Having thus described my invention, what I claim as new therein, and desire to secure by Letters Patent, is—

1. In a fiber scouring and washing machine, a tank provided with an inclined bottom adapted to direct liquid and sedimentary matter to a channel or channels extending from 90 end to end of the tank at the lowest point thereof, means for draining such channel or channels and appliances for flushing the tank-bottom, in combination with a perforated false bottom above said flushing appliances, 95 for the purpose set forth.

2. In a fiber scouring and washing machine, a tank provided with an inclined bottom adapted to direct liquid and sedimentary matter to a channel or channels extending from 100 end to end of the tank at the lowest point thereof, means for draining such channel or channels, and appliances for flushing the tank-bottom, in combination with a washing-trough in, but narrower than, said tank, said washing-trough being arranged above the flushing appliances, for the purpose set forth.

3. In a fiber scouring and washing machine, the combination with the washing tank and trough, and the squeezing-rolls, of a settling-chamber alongside of said trough, a collecting-trough beneath said rolls connected with the settling-chamber, means for purging the settling-chamber of sedimentary matter and means for returning the liquid from said 115 chamber to the washing-trough, for the purpose set forth.

4. In a fiber scouring and washing machine, the combination with the washing tank and trough and the squeezing-rolls, of an open 120 settling-chamber alongside of said tank, said chamber provided with an inclined bottom c' to form a channel c^2 along the outer wall of such chamber, means for draining the same, a collecting-trough beneath the squeeze-rolls 125 connected with said chamber at one end, and means for taking the liquid from the opposite end of the chamber and returning such liquid to the washing-trough, for the purpose set forth.

5. The combination with the tank provided at its feed end with a receiving-chamber having in its inclined front wall a row of openings, and the washing and scouring trough having

its perforated bottom below said row of openings; of the settling-chamber *c* and a pump connected with said chamber and with the receiving-chamber of the tank, for the purpose set forth.

6. The combination with the tank and washing-trough, and a propelling and immersing rake, of the shafts *s s'*, each carrying two weighted levers *L M* and *L' M'* respectively, from which said rake is suspended, a rigid connection between the levers *L* and *L'*, the lever *k'* connected with lever *L*, the cam *k⁴*

on which lever *k'* has bearing, the revoluble crank-shaft *k*, and the slotted lever *l³* in the slot of which the crank on shaft *k* works, 15 said lever *l³* connected with the rake, substantially as and for the purpose set forth.

In testimony that I claim the foregoing as my invention I have signed my name in presence of two subscribing witnesses.

WM. McNAUGHT.
